UNITED STATES PATENT OFFICE.

CRAWFORD M. FAIRBANKS, OF PAWTUCKET, RHODE ISLAND.

TOOL-HANDLE.

SPECIFICATION forming part of Letters Patent No. 286,124, dated October 2, 1883.

Application filed April 27, 1883. (No model.)

To all whom it may concern:

Be it known that I, CRAWFORD M. FAIRBANKS, of Pawtucket, in the State of Rhode Island, have made certain new and useful Improvements in Tool-Handles; and I do hereby declare that the following specification, taken in connection with the drawings making a part of the same, is a full, clear, and exact description thereof.

10 Figure 1 is a section of the handle, showing device for and manner of attaching the tool. Fig. 2 is an edge or side view of the tool and holder. Fig. 3 is an edge view of a portion of a tool with the tang thereof having a modified form of end for engagement in the tool-holder.

15 The object of my invention is to produce a tool-handle which may be used upon a variety of tools having similarly-formed tangs, and which is capable of being attached and detached at pleasure; and it consists in the devices for holding and securing the tool, herein-after described.

20 In the drawings, A is a file, having a tang, B. C is the handle, which is usually made of wood, although other materials may be used, if desired, which is bored out a suitable distance, as shown, and provided with a ferrule, D, at its smaller end, which may extend slightly beyond the wood. Through the handle is a hole or opening, E, into which a nut, F, is introduced and forced inward until the hole in the nut is brought into line with the lengthwise hole in the handle. The tool at the butt-end has shoulders G G upon either side of the tang, the latter terminating in a ball or rim of increased diameter, or in a corrugation for the same purpose, as shown in Fig. 3.

25 H is the tool-holder, having upon its tail-piece I a screw-thread, and having its head J slotted or divided into two prongs, the bottom of such slot being enlarged to receive the enlarged end of the tang when slipped in horizontally.

30 45 Taking the parts substantially as described, the operation of my invention is as follows:

The end of the tang B is inserted in the head of the holder H, as shown in Fig. 2. This being done, the tang and holder are inserted in the handle C and the tail of the latter caused to engage the nut F. As the tool is rotated it is drawn down into the handle by the nut F until the shoulders G G come in contact with the ferrule, when a slight further rotation will put a strain upon the tang, as will be readily seen, which will rigidly hold the tool in position. When it is desired to remove the tool, it is simply turned in the opposite direction until the tail of the holder H is released from the nut F, when the whole can be removed and the tool detached from the holder; or the hole in the handle may be made sufficiently large to permit the removal of the tang from the holder after a few turns to release the tension.

50 55 60 65 70 The manner of holding the tool through the resistance of the shoulders G G against the pull exerted upon the end of the tang B, as described, serves to retain the tool more rigidly in its place than it could be held by any other known means, for the reason that its rigidity in no wise depends upon a continuous lengthwise bearing of the tang in the handle, which would in detachable tools be practically impossible, or, at least, extremely difficult, to 75 secure.

What I claim as my invention, and desire to secure by Letters Patent, is—

75 80 85 The combination of the tool A, having a tang terminating in a ball, corrugation, or enlarged rim, with a holder, H, slotted or divided into two prongs, having an enlarged cavity at the base of the opening or slot between the prongs for the reception of the end of the tang, the nut F, inserted in an opening in the handle, and with the said handle, all substantially as and for the purpose herein set forth.

C. M. FAIRBANKS.
